IGNITION ASSEMBLY

Nelson Elliott, New Westminster, British Columbia, Canada

Application July 13, 1939, Serial No. 284,370

8 Claims. (Cl. 123—143)

This invention relates to an ignition assembly for internal combustion engines.

An object of the present invention is the provision of an ignition assembly particularly for internal combustion engines using oil or other low grade fuels.

Another object is the provision of an ignition assembly adapted to eliminate the necessity of extremely high compressions in the power cylinders of internal combustion engines.

Another object is the provision of a small auxiliary cylinder in which a charge of fuel is fired by the heat of compression and the burning gases are injected into the power cylinder to ignite compressed fuel therein.

A further object is the provision of an ignition assembly for internal combustion engines using oil or the like as fuel, adapted to ensure smooth and even operation of the engine.

A further object is the provision of a device of this character for ensuring complete combustion of the fuel in the engine with which it is used.

Many attempts have been made to eliminate the necessity of extremely high compressions by utilizing an auxiliary piston for injecting burning fuel into a power cylinder to ignite compressed fuel therein. These attempts have been unsuccessful. It is believed that the main reasons for failure are as follows:

1. The charge in the auxiliary cylinder had to be fired while the auxiliary piston was still traveling upwardly, resulting in a knock in the engine and a great strain on the various parts.

2. The charge in the auxiliary cylinder was not completely ignited when it was injected into the power cylinder, resulting in incomplete combustion in the latter.

3. The auxiliary piston was unable completely to clear its cylinder of exhaust gases.

The present invention overcomes these difficulties by providing an assembly in which an auxiliary piston, preferably connected directly to the crank-shaft, is operated in an auxiliary cylinder, said piston being adapted to compress and ignite a charge of fuel therein, and then the piston moves downwardly and upwardly practically through two strokes before a valve opens to allow the ignited fuel to be injected into the main cylinder. This delayed injection affords a time interval in which complete combustion takes place in the auxiliary cylinder before the gases are injected into the power cylinder. By connecting the auxiliary piston to the crankshaft, it is reciprocated steadily and

smoothly. In the known devices of this character, the auxiliary pistons are reciprocated by means of rods riding on cams of various designs, causing the pistons to move suddenly at certain times and to remain stationary at other times.

A feature of this invention is that the auxiliary piston is compressible. In all auxiliary cylinders, ignition must take place before the upper dead centre is reached by the piston. As the valve for admitting the gases into the power cylinder cannot be opened until after ignition has taken place, the pressure in the auxiliary cylinder is still increased after ignition. This means the piston receives a terrific shock and has to work against extremely great pressure. The compressible piston absorbs a good deal of the shock and it is designed to prevent the pressure in the cylinder from rising above a predetermined maximum. The piston is compressed by the gases in the cylinder and when the latter are injected into the power cylinder, the piston assumes its normal position and moves right up to the head of the cylinder completely to expel the gases.

An engine employing the improved ignition assembly is described by way of example, in the following specification and illustrated in the accompanying drawings, in which

Figure 1 is a longitudinal sectional view taken through the internal combustion engine and substantially along the line 1—1 of Figure 3.

Figure 2 is a fragmentary transverse sectional view through the auxiliary cylinder, taken substantially along the line 2—2 of Figure 3.

Figure 3 is a reduced fragmentary plan view of the engine, and

Figures 4 to 7 diagrammatically illustrate one stroke of the auxiliary and power pistons of the engines.

Referring more particularly to the drawings, 10 is the water-cooled block of an internal combustion engine, said block having a removable, water-jacketed head 11, at least one power cylinder 12, and a relatively small auxiliary cylinder 13 for each power cylinder. A power piston 14 adapted to operate in the cylinder 12, is connected to the crank-shaft (not shown) of the engine by a connecting rod 15. A combustion chamber 16 is formed in the head 11 above and communicating with the power cylinder. This chamber overlaps the auxiliary cylinder 13 and a partition 17 separates the chamber from the cylinder, said partition having an injection port 18 therein normally closed by a valve 20. Fuel is supplied to the combustion chamber 16 and ex-

haust gases removed therefrom in any suitable manner such as, for example, through intake and exhaust ports 21 and 22, respectively, formed in the head 11, said ports being controlled by intake and exhaust poppet valves 23 and 24, which are operated in the usual manner. The ports 21 and 22 are connected to intake and exhaust manifolds 25 and 26 (see Figure 3).

An auxiliary piston 27 having piston rings 28, is slidably mounted in the auxiliary cylinder 13. This piston is formed with an upper section 30 spaced from a lower section 31 and joined together by a bolt 32. The bolt 32 is threaded into the lower end of the upper section 30 at 33, and it slidably extends through the top of the lower section 31 at 34. The lower section is secured upon the bolt 32 by a nut 35 threaded on to the lower end of the bolt while a lock nut 36 retains the upper section in its proper position on the bolt. A compression spring 37 surrounding the bolt 32, holds the upper and lower sections of the auxiliary piston apart. The tension on this spring may be regulated by loosening the nut 36 and turning the bolt 32 to move the upper and lower sections towards or away from each other. A connecting rod 38 connects the auxiliary piston to the crank shaft of the engine, the crank of the auxiliary piston being so arranged in relation to the crank of the power piston that the former piston is always behind the latter piston, i. e., the power piston reaches its upper and lower dead centres before the auxiliary piston reaches its upper and lower dead centres, respectively.

A fuel inlet port 40 is formed in the side wall of the auxiliary cylinder 13 near the lower end thereof. This port is so situated that it is just cleared by the auxiliary piston when the latter reaches its lower dead centre. A valve 41 having a stem 42 is normally held seated in the port 40 by a spring 43 and the valve is operated in any suitable manner, such as, by a cam 44 (see Figure 3) mounted on a cam rod 45 and operating in a yoke 46 connected to the stem 42 of the valve. The cam rod is rotatably connected to a rotating part of the motor, such as the drive shaft thereof. The valve 41 operates in a chamber 47 and a fuel pipe 48 connected at one end to the carburetor (not shown) of the engine, is adapted to supply vaporized fuel through a passage 50 formed in the block of the engine, to the chamber 47, whence said fuel passes through the port 40 into the auxiliary cylinder when the former is open.

The valve 20 is slidably mounted in a relatively long bearing sleeve 51 which is mounted on the head 11. The valve is provided with one or more expansion rings 52 similar to piston ring, and it is formed with a reduced portion 53 at its lower end which is adapted to fit into the injection port 18. The upper end of sleeve 51 is formed with a packing gland 54 in which packing 55 is held around the valve 20 by a packing nut 56. A comparatively long casing 57 having a cover 58 is mounted on the head 11 over the bearing sleeve 51 and a cage 60 slidably mounted in said casing, is connected to the upper end of the valve 20. A compression spring 61 is fitted between the top of the cage 60 and the cover 58 and normally holds the valve 20 with the reduced portion 53 closing the port 18. A cam 62, rotated in any suitable manner, operates within the cage 60 to raise the valve 20 sufficiently to open the port 18 at predetermined times, said cam being adapted to make one revo-

lution during two revolutions of the crank-shaft of the engine.

The engine illustrated in the drawings operates on the four cycle principle. Assuming the auxiliary cylinder 13 is charged with vaporized fuel, the auxiliary piston 27 compresses the charge until it is ignited by the heat of compression. The fuel continues to burn while the auxiliary piston moves through a downward and another upward stroke. As the piston approaches the end of its second upward stroke, the valve 20 opens the port 18 and the burning fuel or gases are injected into the combustion chamber 16 where they ignite a charge of fuel that has been compressed by the power piston 14. Then the valve 20 closes the port 18 and the auxiliary piston moves downwardly again creating a vacuum in the auxiliary cylinder. When the piston clears the inlet port, the valve 41 opens said port and a charge of vaporized fuel rushes into the cylinder to fill the vacuum therein. For the sake of convenience, the first, second, third and fourth strokes of the auxiliary piston will be called the compression, burning, injecting and intake strokes, respectively, the first and third strokes being in an upward direction while the second and fourth strokes are in a downward direction.

Figure 7 illustrates the auxiliary piston at its lower dead centre with the valve 41 open to permit the vaporized fuel to enter the cylinder. The auxiliary piston is just about to commence its compression stroke while the power piston 14 has started its exhaust stroke with the exhaust valve 24 open. In Figure 4, the valve 20 is closed and the auxiliary piston nears the point where the fuel is ignited by the heat of compression while the power piston has reached the end of its exhaust stroke. In Figure 5, the auxiliary piston has just started its burning stroke while the power piston is well advanced on its intake stroke with the inlet valve 23 open. Figure 6 shows the auxiliary piston approaching the end of its burning stroke and the power piston at the end of its intake stroke.

Figures 4 to 7 may be used to describe the balance of operation of the pistons, the only difference being the positions of the various valves. With the valves 41 and 24 closed, Figure 7 illustrates the auxiliary piston about to commence its injection stroke and the power piston advanced on its compression stroke. With the valve 20 open, Figure 4 shows the piston 27 at the point where it starts to inject the burning fuel into the combustion chamber 16 to fire the fuel therein to start the power piston on its power stroke, said piston having reached the end of its compression stroke. In Figure 5, with the valve 23 closed, the auxiliary piston has started its intake stroke while the piston 14 is well advanced on its power stroke. In Figure 6, the power piston has reached the end of its power stroke and the auxiliary piston is nearing the end of its intake stroke. Figure 7 illustrates the beginning of the next cycle.

As the auxiliary piston nears the end of its compression stroke, the fuel is ignited by the heat of compression. This results in an explosion and an impact on the piston but the spring 37 absorbs the shock and, therefore, there is no appreciable knock in the engine. This spring is designed to give only at a certain pressure, which pressure is just above that necessary to ignite the fuel. As the piston continues to travel upwardly after ignition has taken place,

the spring 37 absorbs most of the movement so that the pressure in the cylinder does not become too great which might result in an unevenness of operation of the engine and a waste of power. This spring makes it possible to complete the compression stroke of the auxiliary piston without opening the valve 20. As the piston travels through the entire burning stroke and through the greater part of the next injection stroke, the fuel or gases burn in the cylinder. This allows sufficient time for complete combustion to take place. The valve 20 is opened as the piston nears the end of its injection stroke to allow the burning gases to be injected into the combustion chamber. This also reduces the pressure in the auxiliary chamber. The auxiliary piston continues upwardly until it contacts the upper end of its cylinder, at which time the gases are completely ejected from the cylinder and the valve 20 starts to close. The spring 37 makes it possible to have the piston contact the top of the cylinder slightly before its crank reaches its uppermost position so that the piston remains in contact with the top of the cylinder for a short period of time. Then the piston starts on its intake stroke during which it creates a vacuum in the auxiliary cylinder and when the valve 40 is opened, vaporized fuel flows into the cylinder from the carburetor.

As stated above, the auxiliary piston is arranged to travel behind the power piston. The distance may be as desired but it preferably is about one quarter of a stroke. In other words, when the power piston is at the end of its compression stroke, the auxiliary piston is only three quarters way through its injection stroke. The injection valve 20 opens as soon as the power piston reaches the end of its compression stroke so that the burning gases are injected into the power cylinder during the last quarter of the injection stroke of the auxiliary piston and during the first quarter of the power stroke of the power piston.

The valve 41 is operated to open the inlet port each alternate time the auxiliary piston is at substantially its lower dead centre and the valve 20 is operated each alternate time this piston approaches its upper dead centre. Furthermore the valve 20 is operated alternately to the valve 41. In other words, the valve 41 is opened when the piston is at substantially its lower dead centre, then the valves remain closed as the piston moves through its upper and lower dead centres until it approaches the upper dead centre a second time, when the valve 20 opens, and then the valves remain closed as the piston moves through its lower and upper dead centres again until it reaches its lower dead centre a fourth time when the valve 41 opens again.

When the charge of fuel is fired in the auxiliary cylinder, the burning gases remain in said cylinder through substantially two strokes of the piston before they are injected into the power cylinder. This delayed injection after ignition, affords an interval to allow for complete combustion of the gases before they are expelled from the cylinder. The delayed injection also allows sufficient time for the opening and closing of the injection valve. With the piston traveling at high speeds, the delay makes it possible to inject all the burning gases into the power cylinder.

By inserting a compression spring between the auxiliary piston and its reciprocating means, the shock of the explosion as the piston moves

upwardly is absorbed to a certain extent by the spring. The spring also controls the pressure to which the fuel or gases may be compressed and it permits the piston to contact the top of the cylinder to expel all the gases. Furthermore, the spring protects the various parts from damage or breakage should carbon build up on the top of the piston or the cylinder.

The fuel inlet port is positively controlled by 10 a valve so that it is possible to operate the auxiliary piston through two strokes with the burning gases remaining in the cylinder. This also makes it possible to create a vacuum in the cylinder so that the vaporized fuel quickly and completely fills the cylinder as soon as the valve is 15 opened.

While the fuel in the auxiliary cylinder has been described as being ignited by the heat of compression, it will be understood that, if desired, suitable igniting means, such as a spark plug, may be employed. This ignition assembly has been primarily designed for use with engines using low grade fuels but it is to be understood that it may be used with any type of fuel capable of being used in an internal combustion engine.

Various modifications may be made in this invention without departing from the spirit thereof or the scope of the claims, and therefore the exact forms shown are to be taken as illustrative only and not in a limiting sense, and it is desired that only such limitations shall be placed thereon as are disclosed in the prior art or are set forth in the accompanying claims.

What I claim as my invention is:

1. In combination with a power cylinder of an internal combustion engine having a power piston operating therein, an auxiliary cylinder situated adjacent the power cylinder and adapted to be brought into communication therewith, an auxiliary piston operating in the auxiliary cylinder, means for reciprocating the auxiliary piston, an inlet port formed in the auxiliary cylinder adjacent the lower end thereof, a valve adapted to control the inlet port, means for opening the port at predetermined intervals to admit vaporized fuel into the auxiliary cylinder when the auxiliary piston is at substantially its lower dead centre, said fuel being compressed by the auxiliary piston and ignited in its cylinder, valve means at the top of the auxiliary cylinder, and cam means for positively operating the valve means when the fuel in the power cylinder is under compression to permit burning gases to be injected into the power cylinder to ignite the compressed charge of fuel therein.

2. In combination with a power cylinder of an internal combustion engine having a power piston operating therein, an auxiliary cylinder situated adjacent the power cylinder and adapted to be brought into communication therewith, an auxiliary piston operating in the auxiliary cylinder, means for reciprocating the auxiliary piston, an inlet port formed in the auxiliary cylinder adjacent the lower end thereof, a valve adapted to control the inlet port, means for operating the inlet valve to open the port to admit vaporized fuel into the auxiliary cylinder each alternate time the auxiliary piston is at substantially its lower dead centre, said fuel being compressed by the auxiliary piston and ignited in its cylinder, valve means at the top of the auxiliary cylinder, and cam means for positively operating the valve means each alternate time the auxiliary piston approaches its upper dead centre

to permit burning gases to be injected into the power cylinder to ignite a compressed charge of fuel therein, said valve means being operated alternately to the inlet valve.

3. In combination with a power cylinder of an internal combustion engine having a power piston operating therein, an auxiliary cylinder situated adjacent the power cylinder and adapted to be brought into communication therewith, an auxiliary piston operating in the auxiliary cylinder, means for reciprocating the auxiliary piston, means for admitting vaporized fuel into the auxiliary cylinder, said fuel being compressed by the auxiliary piston and ignited in its cylinder, means connected with the auxiliary piston for controlling the pressure of the compressed gases in the auxiliary cylinder, valve means at the top of the auxiliary cylinder, and cam means for positively operating the valve means when the fuel in the power cylinder is under compression to permit burning gases to be injected into the power cylinder to ignite the compressed charge of fuel therein.

4. In combination with a power cylinder of an internal combustion engine having a power piston operating therein, an auxiliary cylinder situated adjacent the power cylinder and adapted to be brought into communication therewith, an auxiliary piston operating in the auxiliary cylinder, means for reciprocating the auxiliary piston, means for admitting vaporized fuel into the auxiliary cylinder, said fuel being compressed by the auxiliary piston and ignited in its cylinder, spring means between the auxiliary piston and its reciprocating means, said spring being adapted to yield when a predetermined pressure is reached in the auxiliary cylinder, valve means at the top of the auxiliary cylinder, and means for operating the valve means at predetermined intervals to permit burning gases to be injected into the power cylinder to ignite a compressed charge of fuel therein.

5. In combination with a power cylinder of an internal combustion engine having a power piston operating therein, an auxiliary cylinder situated adjacent the power cylinder and adapted to be brought into communication therewith, an auxiliary piston operating in the auxiliary cylinder, said auxiliary piston being formed in two sections slidably held together, means connected to the lower section for reciprocating the auxiliary piston, means for admitting vaporized fuel into the auxiliary cylinder, said fuel being compressed by the auxiliary piston and ignited in its cylinder, a compression spring between the two sections of the auxiliary piston, said spring being adapted to yield when a predetermined pressure is reached in the auxiliary cylinder, a valve means at the top of the auxiliary cylinder, and means for operating the valve means at predetermined intervals to permit burning gases to be injected

into the power cylinder to ignite a compressed charge of fuel therein.

6. In combination with a power cylinder of an internal combustion engine having a power piston operating therein, an auxiliary cylinder situated adjacent the power cylinder and adapted to be brought into communication therewith, an auxiliary piston operating in the auxiliary cylinder, said auxiliary piston being connected to a crank formed on the crank-shaft of the engine, an inlet port formed in the auxiliary cylinder, a valve adapted to control the inlet port, means for opening the port at predetermined intervals to admit vaporized fuel into the auxiliary cylinder, said fuel being compressed by the auxiliary piston and ignited in its cylinder, spring means between the auxiliary piston and its reciprocating means, said spring being adapted to yield when a predetermined pressure is reached in the auxiliary cylinder, valve means at the top of the auxiliary cylinder, and means for operating the valve means at predetermined intervals to permit burning gases to be injected into the power cylinder to ignite a compressed charge of fuel therein.

7. In combination with a power cylinder of an internal combustion engine having a power piston operating therein, an auxiliary cylinder independent of and situated adjacent the power cylinder and adapted to be brought into communication therewith, an auxiliary piston operating in the auxiliary cylinder, means for reciprocating the auxiliary piston, means for admitting the vaporized fuel into the auxiliary cylinder, said fuel being compressed by the auxiliary piston and ignited in its cylinder, means for retaining the burning gases in the auxiliary cylinder throughout substantially two strokes of the auxiliary piston, said latter piston being adapted to eject the burning gases into the power cylinder towards the end of said second stroke, spring means on the auxiliary piston permitting the latter to eject all the gases from the cylinder, and means for forming a substantial vacuum in the auxiliary cylinder into which the fresh charge of vaporized fuel is admitted.

8. In combination with a power cylinder of an internal combustion engine having a power piston operating therein, an auxiliary cylinder situated adjacent the power cylinder and adapted to be brought into communication therewith, an auxiliary piston operating in the auxiliary cylinder, means connecting the auxiliary piston to a crank formed on the crank-shaft of the engine, said auxiliary piston being positively reciprocated, means for admitting vaporized fuel into the auxiliary cylinder, said fuel being compressed by the auxiliary piston and ignited in its cylinder, and means for absorbing substantially any shock imparted to the auxiliary piston by the ignition of the fuel.

NELSON ELLIOTT.
